SWIVEL ELECTRIC CONNECTION

Josef F. Mose, Point Loma, Calif.

Application May 12, 1936, Serial No. 79,247

2 Claims. (Cl. 173—324)

My invention relates to a swivel electric connector, and the objects of my invention are:

First, to provide an electrical connector that is provided with a swivel to prevent the electric wire from becoming twisted and snarled and therefore quickly deteriorate.

Second, to provide a connector of this class which is very efficient in its action.

Third, to provide a connector of this class in which there is a minimum of arcing.

Fourth, to provide a connector of this class which is positive in its action.

Fifth, to provide a connector of this class where one member revolves so easily, relatively to the other that any slight turning of the wire will be immediately taken up by the connector.

Sixth, to provide a connector of this class which is very simple and economical of construction, easy to operate, easy to install, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application, in which:

Figure 1 is a sectional view along the line 1—1 of Fig. 2; Fig. 2 is a transverse sectional view along the line 2—2 of Fig. 1, and Fig. 3 a transverse sectional view along the line 3—3 of Fig. 1.

Similar characters of reference refer to similar parts and portions throughout the several views of the drawing.

Casing member 1, casing cap 2, revoluble core 3, cap connecting screw 4, ball supporting angles 5 and 6, ball supporting angles 7 and 8, balls 9 and 10, contacts 11, 12, 13, 14, conductor 15 and conducting terminals 16 and 17 constitute the principal parts and portions of my swivel electric connector.

The casing member 1 is made of any suitable non-conducting material and provided with an enlarged bore 1a at its upper end, and a reduced bore, 1b, at its lower end. Mounted in these bores 1a and 1b is a core member 3 which is also made of insulating material provided with enlarged upper portion 3a which fits freely in the bore 1a, and with the reduced separate tapered lower portion 3b which fits freely in the conforming bore 1b, shown best in Fig. 1 of the drawing. It is preferred that the enlarged portion 3a extend

slightly above the upper end of the casing 1, as shown best in Fig. 1 of the drawing.

Mounted over the upper end of the members 1 and 3 is a cap member 2 which rests against the upper end of the member 1 and is provided with a recess portion centrally therein for receiving the upper end of the member 3.

Mounted in the upper outer side of the revoluble core member 3 is an annular angle member 6 supported therein by extensions 6a, and mounted in the recess in the cap member 2 is an annular angle member 5 supported by extensions 5a, and interposed between the members 5 and 6 are a row of balls 9, thus providing ball bearings between the revoluble core 3 and the cap 2. Connecting with the annular member 5 by means of the extension 5a is the conductor terminal 16, which connects with any source of electrical energy and connecting with the extension 6a is contact member 11 which extends down through the member 3a to the lower end of said member and into the member 3b, as shown best in Fig. 1 of the drawing, and connected with this member 11 is another contact member 12, which is a spring contact for receiving the electrical contact of an electrical equipment.

Mounted at the juncture of the reduced portion 1b and the enlarged portion 1a of the casing 1 is an annular angle member 7, and mounted in the core member 3 is a similar angle member 8 supported by the screw 8a. Screw 8a also supports a contact member 13 which extends downwardly to the lower extremity of the member 3b, and secured thereto is also another spring contact member 14 for receiving the other contact member of an electrical equipment. Connecting with the angle 7 is a conductor 15 which extends upwardly on the inner side of the large bore of the casing 1, then outwardly at right angles and is provided with a hole which is threaded, that connects with the screw 4, which screw 4 holds the cap 2 rigidly in position on the casing 1 and over the upper end of the core member 3, and also serves as a conductor, as the other inward conductor terminal 17 extends downwardly through the cap and connects with the screw member 4, as shown best in Fig. 1 of the drawing, there being provided a separate insulating member 2a between said conducting terminal 17 and the annular angle member 5.

It will be here noted that the members 3a and 3b are separate members held together by the bolt 3c and prevented from turning by the webb 3d in a conforming groove in member 3a. It will be further noted that applicant uses a compound

50

55

in connection with the ball bearings 9 and 10, and angular housings to prevent arcing, which compound consists of an animal oil and a small amount of graphite, mixed together to form a paste.

The operation of my swivel electric connector is as follows: The terminals 16 and 17 connect with any source of electrical energy and the contacts 11 to 14 inclusive, connect with contacts of any electrical equipment. Any twist in the terminal conductors 16 and 17 will be readily taken up as the casing 1 and cap 2 will revolve relative to the core 3, and this revolution is mounted on ball bearings which provide very easy rotation, and the separate electric conductors through the connector, clearly carry the current along the proper line to the contacts, without any chance of leakage, and in which the arcing is reduced to a minimum.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a swivel electric connector, the combination with a casing member provided with an enlarged bore at one end and with a reduced tapered bore communicating therewith, a casing cap adapted to fit one end thereof, a revoluble core member conforming to said bore filling the same and provided with a separate tapered portion conforming with and filling the reduced bore in said casing and extending at its opposite end some distance into said casing cap, a ball supporting annular angle member mounted in said casing cap, another ball supporting annular angle member mounted at the opposite end of said enlarged bore at the juncture of said reduced bore portion and corresponding opposed angle members mounted on said revoluble core at its opposite ends, ball bearings interposed between said angle members, an electric conductor extending into said casing cap to the upper ball bearing angle members then downwardly through said revoluble core member and terminating in an electrical equipment contact in the reduced separate portion of said core member, another electrical conductor extending through said casing cap and casing and connected with the lower ball bearing angle members and thence through said core members and connecting with an electrical equipment contact supported in the reduced portion of said revoluble core, a cap connecting screw connecting said casing cap with said casing and serving as a portion of one of the electrical conductors through said casing cap and casing, and a bolt connecting said core with the separate reduced portion of said core.

ball bearing angle members then downwardly through said revoluble core member and terminating in an electrical equipment contact in the reduced separate portion of said core member, another electrical conductor extending through said casing cap and casing and connected with the lower ball bearing angle members and thence through said core members and connecting with an electrical equipment contact supported in the reduced portion of said revoluble core, a cap connecting screw connecting said casing cap with said casing and serving as a portion of one of the electrical conductors through said casing cap and casing.

2. In a swivel electric connector, the combination with a casing member provided with an enlarged bore at one end and with a reduced tapered bore communicating therewith, a casing cap adapted to fit one end thereof, a revoluble core member conforming to said bore filling the same and provided with a separate tapered portion conforming with and filling the reduced bore in said casing and extending at its opposite end some distance into said casing cap, a ball supporting annular angle member mounted in said casing cap, another ball supporting annular angle member mounted at the opposite end of said enlarged bore at the juncture of said reduced bore portion and corresponding opposed angle members mounted on said revoluble core at its opposite ends, ball bearings interposed between said angle members, an electric conductor extending into said casing cap to the upper ball bearing angle members then downwardly through said revoluble core member and terminating in an electrical equipment contact in the reduced separate portion of said core member, another electrical conductor extending through said casing cap and casing and connected with the lower ball bearing angle members and thence through said core members and connecting with an electrical equipment contact supported in the reduced portion of said revoluble core, a cap connecting screw connecting said casing cap with said casing and serving as a portion of one of the electrical conductors through said casing cap and casing, and a bolt connecting said core with the separate reduced portion of said core.

JOSEF F. MOSE.
